(57) **CLAIM**

The ornamental design for computer mouse, substantially as shown and described.

DESCRIPTION

FIG. 1 is a front, bottom and left side perspective view of computer mouse, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of computer mouse, which form no part of the claimed design.
